Primary Examiner — Cathron Brooks*Assistant Examiner* — Ian Whitmore(74) *Attorney, Agent, or Firm* — Wilson Sonsini Goodrich & Rosati(57) **CLAIM**

The ornamental design for a computer display panel with graphical user interface, as shown and described.

DESCRIPTION

FIG. 1 is a front view of a computer display panel with graphical user interface showing a first embodiment of our new design;

FIG. 2 is a second embodiment thereof;

FIG. 3 is a third embodiment thereof;

FIG. 4 is a fourth embodiment thereof; and,

FIG. 5 is a fifth embodiment thereof.

The broken lines in the drawings represent portions of the computer display panel that form no part of the claimed design.

1 Claim, 5 Drawing Sheets(56)
